UNITED STATES PATENT OFFICE.

ARTHUR C. ROWLEY, OF PHILADELPHIA, PENNSYLVANIA, ASSIGNOR TO ASSOCIATED AUTOMATIC SPRINKLER CO., OF PHILADELPHIA, PENNSYLVANIA, A CORPORATION OF DELAWARE.

ALARM-CHECK VALVE.

1,137,025.

Specification of Letters Patent. Patented Apr. 27, 1915.

Application filed February 10, 1914. Serial No. 817,750.

all whom it may concern:

Be it known that I, ARTHUR C. ROWLEY, a citizen of the United States, and a resident of the city of Philadelphia, State of Pennsylvania, have invented certain new and useful Improvements in Alarm-Check Valves, of which the following is a specification, reference being had to the accompanying drawings.

10 One object of this invention is to provide an improved alarm check valve including a casing, and a main valve or clapper, and auxiliary or alarm valve inclosed in the casing, and in which the auxiliary valve is arranged to move as a result of the movement of the main valve, and may be so adjusted as to begin to open simultaneously with the main valve so as to give an alarm as soon after the inception of an opening 20 movement of the latter as the mechanical functions necessary for the operation of the alarm proper can be fulfilled and which in practice require only an extremely short period of time, or so adjusted as to give the main valve a predetermined amount of "lead" in its opening movement with respect to the opening movement of the auxiliary valve, so as to delay the operation of the alarm for a further brief interval of 30 time after the inception of an opening movement of the main valve, to allow for "water hammer" or other brief variations in pressure.

A further object of this invention is to 35 provide an improved alarm check valve including a casing provided with a supply opening and a discharge opening adapted to communicate with a supply pipe and a discharge pipe respectively, and provided 40 with an opening normally closed by a removable cover or bonnet, and movable members including a main valve and an auxiliary valve arranged in the casing and conveniently accessible and removable through the latter opening when the cover is removed 45 and without disturbing the supply pipe or the discharge pipe.

Other objects of this invention will appear hereinafter.

50 In the accompanying drawings, Figure 1 is a longitudinal section of an alarm check valve constructed in accordance with this invention; Fig. 2 a transverse section on line 2-2 of Fig. 1; Fig. 3 a fragmentary side

elevation of a portion of the same; Fig. 4 a fragmentary side elevation partially in central longitudinal section of a modified form of this invention; and Fig. 5 a transverse section on line 5-5 of Fig. 4.

Referring to the drawings, one embodiment of this invention comprises a hollow casing 9, including a hollow main or body portion 10 provided at one end with an inlet or supply opening 11 and at its opposite end with an outlet or discharge opening 12, these two openings 11 and 12 being substantially circular in shape and arranged coaxially with the body portion 10 of the casing, and forming portions of a main passage through the casing. The body portion 10 of the casing is preferably provided with two flat parallel annular flanges 13 and 14, preferably integral therewith and surrounding the inlet and outlet openings respectively and coaxial therewith. These flanges are provided with suitable apertures 15 and 16 through which bolts may be inserted for connecting the casing to suitable supply and discharge pipes (not shown) respectively. The interior of the casing 9 is divided into an inlet compartment 20 communicating with the inlet 11, and an outlet compartment 21 communicating with the outlet 12, by means of a transverse approximately annular partition 22, preferably integral with the casing and the inner marginal portion of which is preferably arranged in a plane inclined slightly with respect to the longitudinal axis of the body portion 10 of the casing. The body of the casing may also be provided with a threaded opening 23 through one side thereof and communicating with the inlet compartment 20 and adapted to receive a drain pipe (not shown).

The body 10 of the casing is provided with a transverse or lateral substantially cylindrical hollow extension 24, preferably integral therewith, the longitudinal axis of which preferably intersects and is perpendicular to the longitudinal axis extending through the body portion 10 of the casing. The interior of this extension communicates with the outlet compartment 21. The outer end of this extension forms a flat annular seat 25, surrounding a substantially circular opening 26, and mounted upon this seat is a cover or bonnet 27 provided with a flat marginal flange 28 preferably integral therewith.

and which is clamped securely to the seat 25 by means of bolts 29 extending loosely through the flange 28 and threaded into the seat. For a purpose which will appear hereinafter, this cover 27 is provided centrally with a corrugation 30 forming an internal recess 31 extending in a direction substantially parallel to the longitudinal axis of the body portion of the casing, and the cover 10 may be provided centrally with a tapped aperture 32 adapted to receive a pipe for connecting the outlet compartment 21 with a pressure gage.

For controlling the flow of water, steam 15 or other fluid through the main passage between the supply opening 11 and the outlet opening 12, there is arranged within the body portion 10 of the casing and between the annular partition 22 and the outlet opening 12, a substantially circular main valve or clapper 35 which is provided upon its inlet side with a flat annular marginal surface 36 which is proportioned and arranged to cooperate with an annular valve seat 37 25 which is threaded into the annular partition 22 and which is provided with a comparatively narrow flat bearing edge 38 which is arranged in a plane slightly inclined with respect to the longitudinal axis of the body 10 of the casing and substantially parallel to the plane of the inner marginal portion of the partition 22, and against which the flat marginal under surface 36 of the main valve engages when the main valve is closed.

For supporting the main valve 35 to oscillate with respect to its seat 37 about a fixed axis coincident with the flat marginal under surface 36 of the valve regardless of the position of the valve, and coincident with the bearing edge 38 of the valve seat, the main valve is provided with two substantially parallel arms 45 preferably integral therewith and projecting therefrom approximately in a plane therewith and toward the cover 27. The outer ends of these arms are enlarged and form two substantially cylindrical spaced coaxial bearings 46, which are snugly but rotatably mounted upon a cylindrical pivot 47 extending therethrough 50 and the longitudinal axis of which is coincident with the plane of the bearing edge 38 of the main valve seat 37 and substantially parallel to the plane of the flat annular end 25 of the hollow extension 24 of the casing. 55 The ends of the pivot 47 fit tightly in two lugs 48 and 49 respectively preferably integral with and projecting inwardly from the casing 9, and the inner ends of which are engaged snugly but rotatively by the outer 60 ends of the bearings 46 whereby the bearings are held against movement longitudinally with respect to the pivot 47. The main valve 35 is cupped or depressed centrally as at 50 throughout the major portion of its 65 area and in the direction of the inlet open-

ing 11, and the main valve is provided upon its outlet side with a lug 51 preferably integral therewith which is adapted to act as a stop to hold the valve when in a full open position, as will appear hereinafter. 70

For the purpose of sounding or otherwise giving an alarm when the main valve 35 swings into an open position, there is provided an auxiliary valve 55 which cooperates with an auxiliary valve seat 56 provided with a longitudinal central cylindrical valve port 57 through which communication is had between the outlet compartment 21 and the inner end of a cored or bored alarm passageway or by-pass 58 provided therefor 80 in a lug 59 which projects inwardly from the casing 9 into the outlet compartment 21 and the inner end of which is inclined toward the central portion of the cover or bonnet 27. The auxiliary valve seat 56 is preferably in the form of a removable bushing, one end of which is threaded into the lug 59, as at 60, and the other end of which is exteriorly in the form of a truncated cone, as at 61, and terminates in a comparatively 85 narrow flat annular bearing surface 62, coaxial with the auxiliary valve 55 when the auxiliary valve is in position against the seat. This bearing surface 62 is preferably spaced from the plane of the bearing surface 90 38 of the main valve 35 and in a plane forming an obtuse angle with the plane of the latter bearing surface. The outer end of the passageway or by-pass 58 communicates with a transverse passage 65 extending 95 through the wall of the casing 9 and the opposite ends of which are preferably threaded as at 66 and 67 to receive outlet pipes 68 and 69 leading to any well known or suitable alarm device or devices, (not 100 shown), whereby when steam or other fluid is admitted through the valve port 57, an alarm or alarms will be given.

For actuating the auxiliary valve 55 to open either simultaneously with the opening of the main valve 35 or at a predetermined and adjustable interval after the opening of the main valve 35, the auxiliary valve 55 comprises a substantially cylindrical body portion having a flat inner surface arranged to engage against the auxiliary valve seat 56 and is provided with a cylindrical stem 70 projecting outwardly therefrom and preferably integral and coaxial therewith and the outer end of which engages snugly but slidably in a cylindrical axial recess 71 provided therefor in the inner end of a plug 72.

The plug 72 is threaded into the outer end of a sleeve 73 coaxial therewith, which projects inwardly from the inner end of the plug and the inner portion of which loosely surrounds the body portion of the auxiliary valve 55 and is provided upon its inner end with an inwardly projecting marginal 120 125 130

portion of which is arranged to engage the outer surface of the auxiliary valve 55 to lift the auxiliary valve away from its seat. The stem 70 is provided with a suitable recess provided with a shoulder 71, the upper end of the plug 72, is provided with a shoulder 73, normally held in a state of engagement longitudinally between the shoulder 71 and the outer surface of the body 50, so that the auxiliary valve 55, and normally held in a position to close the auxiliary valve seat 56 or against the shoulder 71, may be readily disengaged with a longitudinal pull on the stem 70, or other suitable means, so as to allow the water to pass through the plug and valve 55, and out through the lower end of the valve 55, so as to effect the seating of the auxiliary valve 55. This arrangement is also useful in permitting a quick and efficient measurement of the water pressure at the auxiliary valve by passing a suitable tube or probe into the auxiliary valve and holding it in a position to extend the water stream from the auxiliary valve 55.

the plug 72 is also in the form of a hexagon or other suitable shape in cross-section, for convenience in adjustment.

From the foregoing, it is evident that the arrangement and construction of the auxiliary valve 55 and the parts coöperating therewith are such that in the operation of this device, the sleeve 73 surrounding the auxiliary valve 55 moves in unison with the lever 80 and main valve 35, and that the sleeve 73 may be adjusted longitudinally so as to permit of any desired amount of "lead", within prescribed limits, of the main valve 35 in respect to the auxiliary valve 55, in the opening of the main valve 35, or the sleeve 73 may be adjusted so that the main valve and the auxiliary valve will open practically simultaneously. When the sleeve 73 is adjusted as shown in Fig. 1 to permit the main valve 35 to open slightly in advance of the auxiliary valve 55, the auxiliary valve 55 is held against its seat 56 by the spiral spring 75 during the first movement of the main valve in opening, and during this movement, the lever 80 and sleeve 73 carried thereby swing slightly about the pivot 47 with respect to the auxiliary valve 55, which is, during this movement, held against its seat 56 by the spring 75. When the main valve 35 has opened a sufficient distance to bring the flange 74 of the sleeve 73 into engagement with the marginal portion of the auxiliary valve 55, a further movement in the same direction of the main valve acts to lift the auxiliary valve from its seat. When the main valve 35 is in its full open position, the lug 49 of the main valve lever 80 abuts against the lug 59 of the casing. During the latter and major portion of the movement of the main valve from a closed to a full open position, the outer end of the valve lever 80 and the parts carried thereby will move freely through the internal passage 81 provided therefor in the cover 82.

To permit of the convenient removal of 110 the hereinbefore described movable parts contained in the casing 9, the axial openings through the lugs 48 and 49 are extended through the exterior walls of the casing to permit of the removal of the pivot 47 115 longitudinally in either direction from the casing, the outer end of these openings being preferably normally closed by two cap screws 50 threaded into the outer ends of the openings from the outside of the casing 120. said action to hold the pivot 47 against longitudinal movement.

the improved alarm check valve, the cover 3 and its cover or hornet 27, and the movable and detachable parts contained in the housing are so constituted and arranged that in the removal of the cover 27, convenient access may be had to all of the movable or detachable elements or parts contained in the casing, and so that all of these 130

- parts may be conveniently adjusted or removed and replaced through the opening controlled by the cover 27. The auxiliary valve 55 and the adjustable parts surrounding the same, are located at a considerable distance from the main valve and out of the direct path of the main current of water through the casing, thus avoiding any interference by accumulations of sediment which would cause false alarm. The auxiliary valve is also located nearer than the main valve to the cover 27 and in such a position that adjustment of the auxiliary valve to vary the "lead" of the main valve may be conveniently effected. When in operative position, this improved alarm check valve is usually arranged so that the longitudinal axis through the inlet 11 and outlet 12 is substantially horizontal and the cover 27 is on the upper side of the casing, with the drain pipe opening 23 on the under side of the casing, but the casing may be arranged vertically or in any other suitable position.
- 25 Instead of constructing and mounting the auxiliary valve as heretofore described and as shown in Figs. 1 and 2, the auxiliary valve may be constructed and mounted as shown in Fig. 4. In this modified form the auxiliary valve 100 is mounted to reciprocate in a sleeve 101 which is threaded into one end of a lever 102 which is mounted to oscillate about the pivot 47 in the same manner that the lever 80 shown in Figs. 1 and 2, is mounted, but in this modified form the inner end of the lever 102 is adjustably connected to the main valve 35 by a cap screw 103 which extends loosely through an aperture 104 provided therefor in the inner end of the lever 102, and is threaded into and is longitudinally adjustable with respect to the main valve 35, being held in any position of adjustment by a lock nut 105 bearing against the main valve. The outer end of the screw 103 is provided with a head 106, which is normally so arranged as to permit of a limited free movement of the inner end of the lever 102 longitudinally of the screw 103.
- 50 In this modified form the auxiliary valve 100 is provided with a stem or hub 107 and radial ribs 107' integral therewith the outer longitudinal edges of the ribs forming guides for the valve, and a plug 108 is threaded into the outer end of the sleeve 101, and is provided upon its inner end with a cylindrical projection 109 which engages loosely in a cylindrical aperture 110 provided therefor in the inner end of the valve stem 107. The plug 108 is provided centrally with a comparatively small longitudinal aperture 111 for the reason hereinbefore stated in describing the aperture 76 of the plug 72 of the first form of this invention. In the modified form no longitudinal adjustment of the sleeve 101 is necessary as the time of the opening of the auxiliary valve with respect to the main valve may be adjusted by adjusting the cap screw 103 so as to have the auxiliary valve opened either simultaneously with or shortly after the opening of the main valve.
- 55 In the form of invention shown in Figs. 1 and 2 the spiral spring 75 may ordinarily be omitted as the auxiliary valve will ordinarily be drawn into and held in position on its seat by the siphonic or other action of the water or other fluid passing outwardly through the alarm passage 58. In the form of the invention shown in Fig. 4 a spiral spring 80 may be inserted between the horizontal valve and the plug, if desired although ordinarily for reasons just stated this would not be necessary.
- 60 Although only a single form has been shown in which this invention may be embodied, it is to be understood that the invention is not limited to the specific form shown, but might be embodied in various forms without departing from the spirit of this invention or the scope of the appended claims.
- 65 Having thus fully described this invention, I claim and desire to protect by Letters Patent of the United States:
1. An alarm check valve comprising a casing, a main valve inclosed in said casing and arranged to oscillate about a fixed axis with respect thereto, an auxiliary valve, and means detachably connected to said main valve for oscillating said auxiliary valve, said auxiliary valve having a limited movement with respect to said main valve.
  2. An alarm check valve comprising a casing, a main valve inclosed in said casing and arranged to oscillate about a fixed axis with respect thereto, an auxiliary valve, means detachably connected to said main valve for oscillating said auxiliary valve, said auxiliary valve having a limited movement with respect to said main valve, and yielding means tending to move said secondary valve with respect to said main valve.
  3. An alarm check valve comprising a casing, a main valve arranged in said casing, a pivot upon which said main valve is arranged to oscillate, a lever arranged to oscillate upon said pivot and detachably connected to said main valve, and an auxiliary valve arranged to be actuated by said lever.
  4. An alarm check valve comprising a casing, a main valve arranged in said casing, a pivot upon which said main valve is arranged to oscillate, a lever arranged to oscillate upon said pivot and detachably connected to said main valve, and an auxiliary valve arranged to be actuated by said lever, and having a limited movement with respect thereto when in operation.
  5. An alarm check valve comprising a

casing, a valve arranged in said casing, a pivot extending in said casing and carried thereby and upon which said valve is arranged to oscillate, a lever mounted upon said pivot and an auxiliary valve carried by said lever, said pivot being removable longitudinally from said casing and from engagement with said lever.

6. An alarm check valve comprising a casing, providing a main passageway and an alarm passageway, a main valve arranged to control said main passageway, and an auxiliary valve arranged to control said alarm passageway and means detachably connected to said main valve for moving said auxiliary valve, said auxiliary valve being arranged to permit said main valve to open in advance of the opening of said auxiliary valve.

7. An alarm check valve comprising a casing, a main valve inclosed thereby and arranged to oscillate with respect thereto about a predetermined axis, an auxiliary valve, and means arranged to oscillate about said axis and in unison with said main valve and detachably connected to said main valve for actuating said auxiliary valve, said means being adjustable with respect to said main valve to permit said main valve to open in advance of said auxiliary valve.

8. An alarm check valve comprising a casing, a valve arranged in said casing, a pivot extending in said casing and carried thereby and upon which said valve is arranged to oscillate, a lever mounted upon said pivot and detachably connected to said valve, and an auxiliary valve carried by said lever.

9. An alarm check valve comprising a casing, a valve arranged in said casing, a pivot extending in said casing and carried thereby and upon which said valve is arranged to oscillate, a lever mounted upon said pivot and detachably connected to said valve, and an auxiliary valve carried by said lever, said pivot being removable longitudinally from said casing and from engagement with said first-mentioned valve and said lever.

10. An alarm check valve comprising a casing, a main valve inclosed thereby and arranged to oscillate with respect thereto about a predetermined axis, a bell crank lever arranged to oscillate about said axis in

unison with said main valve and having one end detachably connected to said main valve, and an auxiliary valve carried by the other end of said lever and having a limited movement with respect thereto to permit said main valve to open in advance of said auxiliary valve.

11. An alarm check valve comprising a casing, a main valve inclosed thereby and arranged to oscillate with respect thereto about a predetermined axis, an element arranged to oscillate about said axis in unison with said main valve, an auxiliary valve provided with a stem and arranged to be carried by and to reciprocate with respect to said element, and yielding means surrounding said stem and tending to press said auxiliary valve in a predetermined direction with respect to said element.

12. An alarm check valve comprising a casing, a main valve inclosed thereby and arranged to oscillate with respect thereto about a predetermined horizontal axis, and an auxiliary valve arranged in said casing to be oscillated about said axis by the movement of said main valve, said main valve and said auxiliary valve being upon opposite sides of a vertical plane coincident with said axis when said main valve is closed.

13. An alarm check valve comprising a casing, a main valve inclosed thereby and arranged to oscillate with respect thereto about a predetermined horizontal axis, and an auxiliary valve arranged in said casing to be oscillated about said axis by the movement of said main valve, said main valve and said auxiliary valve being upon opposite sides of a vertical plane coincident with said axis when said main valve is closed, said casing being provided with a door arranged upon the same side of said plane as said auxiliary valve when said main valve is closed.

In witness whereof, I have hereunto set my hand this ninth day of February A. D., 1914.

ARTHUR C. ROWLEY.

Witnesses:

A. IRWIN GARDNER,
ALEXANDER PARK.

It is hereby certified that in Letters Patent No. 1,137,025, granted April 27, 1915, upon the application of Arthur C. Rowley, of Philadelphia, Pennsylvania, for an improvement in "Alarm-Check Valves," an error appears in the printed specification requiring correction as follows: Page 4, line 75, for the word "auxility" read *auxiliary*; and that the said Letters Patent should be read with this correction therein that the same may conform to the record of the case in the Patent Office.

Signed and sealed this 18th day of May, A. D., 1915.

[SEAL.]

R. F. WHITEHEAD,
Acting Commissioner of Patents.
